UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

HEATING SYSTEM FOR INCUBATORS.

Application filed February 11, 1920. Serial No. 357,876.

To all whom it may concern:

Be it known that I, HENRY M. SHEER, a citizen of the United States, residing at Quincy, in the county of Adams and State of Illinois, have invented certain new and useful Improvements in Heating Systems for Incubators, of which the following is a specification.

My invention relates to an improvement 10 in heating systems for incubators, and the like, and the object is to provide means for conserving heat from a single burner for one or more units, according to the requirements of the operator, one of the ideas of 15 this invention being the creation of uniform pressure of heated air and its rapid circulation through the incubator under automatic control, whether it be in a single unit or a plurality of units.

20 The invention consists in a drum in which the air is confined and heated to a high and uniform degree throughout, and a system of piping into which the heated air from the drum is adapted to discharge under automatic control, the pipe system providing 25 for a circuitous course of the air throughout the area to be heated, and contemplating a return and final discharge over the point of inlet, where the heat is most intense, so that 30 the movement of the circulating air is further facilitated by the creation of a vacuum or suction in addition to the pressure of the heated air, the two forces co-operating to 35 create a rapid movement and circulation of the heated air.

In the accompanying drawings:—

Fig. 1 is a view in perspective showing a multideck arrangement of incubator units;

Fig. 2 is a plan view of the pipe system; 40 Fig. 3 is a vertical section through the drum and suction-chamber; and

Fig. 4 is a detail horizontal section through the suction chamber.

The numeral 1 represents one or more 45 units, three being shown in a multideck arrangement in Fig. 1, on one side of the central heating plant, and it is understood the invention contemplates an equal number of multideck units on the opposite side, projection being made therefor.

The numeral 2 indicates the heating drum. This also is made in as many sections as there are incubator units, in other words there is one section for each incubator unit, 55 and these sections fit together after the

manner of an ordinary stove pipe, the uppermost section, of course, being closed at the top, and the lowermost section open at the bottom, and provided with an extension 3 capable of being adjusted to the position 60 and height of the burner 4 beneath the same. Each drum section has two outlets 5 extending in opposite directions, and these are automatically controlled by bell-crank dampers 6, which have similar thermostatic 65 connection 7, whereby the dampers are regulated by the heat within the incubator.

The pipe system consists of a central pipe 8, two side return pipes 9 and 10 parallel therewith, and end pipes 11, 12 and 13 in 70 general rectangular form with relation to one another. These side return pipes 9 and 10 are in open communication with one another, the central distributing pipe 8 leading directly out of the end of the rectangular suction chamber 14, and the pipes 12 and 13 returning from the opposite sides of the pipe system and discharging at opposite points into said suction chamber 14.

The supply pipe 15 extends throughout 80 the length of the suction chamber and some distance into the forward end of the central distributing pipe 8, where it discharges, it being of considerably less diameter than the latter, and into the pipe 15 one of the outlet pipes 5 of the drum is inserted. The chimney 17 for the heated air leads upwardly from the end of the suction chamber adjacent to the drum. In this way the chimney is directly over the inlet, where the 90 heat of the air from the drum is most intense, thus producing a vacuum or suction, and together with the pressure from the hot air-filled drum it further greatly facilitates the movement of the hot air through the 95 entire system.

In this way, no air whatever is discharged into the incubator or chamber itself, but the air is circulated rapidly therethrough throughout the entire pipe system, 100 first through the center, thence to the farthest end, thence to the sides, and back to the suction chamber, and out where the suction or vacuum is necessarily the greatest, where the chimney is located.

Since the heat is greatest through the central distributing pipe 8, an asbestos-lined board 18 is placed therebeneath.

It is understood that the air is forced in under pressure, on the principle of the well- 110

known water injector. That is to say the supply pipe 15 into which the heated air from the drum is fed extends well into the central distributing pipe 8 and beyond the 5 inner ends of the side return pipes 12 and 13. Hot air is thus forced by pressure in the direction of the rear through the central distributing pipe 8, but at the same time a vacuum or suction is created at the 10 inner ends of the return pipes 12 and 13 in the suction-chamber 14, so that while there is constant and uniform pressure from the heating drum through the central distributing pipe 8, there is a vacuum created at 15 the discharge ends of the return pipes 12 and 13 at all times, and by reason of the pressure and suction there is a quick circulation and return, and in consequence uniform heating of the air which finally discharges through the chimney 17 at a point 20 where the heat is the most intense, thus resulting in the creation of a partial vacuum and further suction of the returning and discharging air at that point.

25 I claim:

1. A hot air system including a central distributing pipe, side return pipes parallel therewith, an end pipe connected with the central distributing pipe and with the 30 side return pipes, a supply pipe extending into the central distributing pipe, a suction chamber surrounding said supply pipe and communicating with said return pipes, and a source of heat discharging into said supply pipe.

2. The combination with an incubator

unit, of a heater having an outlet with means for controlling said outlet, an air heating system including a central distributing pipe, side return pipes parallel therewith, an end pipe connected with the central distributing pipe and with the side return pipes, a supply pipe extending into the distributing pipe, and into which the outlet from the heater discharges, and a 40 suction chamber surrounding said supply pipe and communicating with said side return pipes.

3. The combination with an incubator unit, of an air heating system including a 50 central distributing pipe with side return pipes parallel therewith, an end pipe connected with the central distributing pipe and with the side return pipes, a supply pipe extending into the distributing pipe, 55 a suction chamber surrounding said supply pipe and communicating with said side return pipes, and a source of heat discharging into said supply pipe.

4. A hot air system including a distributing pipe, a return pipe, a pipe for connecting the distributing pipe with the return pipe, a supply pipe extending into the distributing pipe, a suction chamber surrounding the supply pipe and communicating with the return pipe and with the distributing pipe, and a source of heat discharging 60 into the supply pipe.

In testimony whereof I affix my signature.

HENRY M. SHEER.
